UNITED STATES PATENT OFFICE.

ORLANDO V. CATER, OF HARVEY, ILLINOIS, ASSIGNOR TO NATIONAL DRILL AND MANUFACTURING COMPANY, OF CHICAGO, ILLINOIS, A CORPORATION OF WEST VIRGINIA.

WELL-MACHINE.

SPECIFICATION forming part of Letters Patent No. 789,589, dated May 9, 1905.

Application filed February 21, 1903. Serial No. 144,385.

To all whom it may concern:

Be it known that I, ORLANDO V. CATER, a citizen of the United States, residing at Harvey, in the county of Cook and State of Illinois, have invented certain new and useful Improvements in Well-Machines, of which the following is a specification.

My invention relates to well-machines in which the rope or cable to which a "drilling" or "spudding" tool is attached is carried from a rotary winding-drum to and over an overhead pulley at the upper portion of a derrick, so as to permit the tool attached to its free-end portion, which depends from such overhead pulley, to perform its required work, the "jumping" or vertical reciprocation of the tool being effected by passing the rope or cable about a pulley which is mounted upon a walking-beam and arranged to engage the rope or cable at a point between the winding-drum and the overhead pulley on the derrick. In machines of such character the walking-beam, so far as I am aware, has generally been arranged substantially horizontal. Objects of my invention are to increase the length of stroke or reciprocation on the part of the tool employed, to lessen the power required for operating the vibratory beam, to place the beam as a whole nearer the derrick, and thereby shorten the length of the machine and render it more compact, and to provide a simple, compact, and effective device for controlling the winding-drum.

In the accompanying drawings, Figure 1 is a side elevation of a portion of a well-machine embodying my invention. Fig. 2 is a top plan view. Fig. 3 is a detail view showing the brake device employed. Fig. 4 is a side elevation as in Fig. 1 with the pulleys K and L omitted and connection between the beam H and the rope or cable attained through the medium of certain devices illustrated. Fig. 5 shows a portion of the machine in side elevation and includes a derrick with an overhead pulley thereon.

The rope or cable A is attached at one end to a winding-drum B, Fig. 2, and is understood

to be extended upwardly therefrom to any known or suitable overhead pulley or pulley system at the upper portion of an ordinary derrick, illustration of such overhead pulley A' at the upper portion of a derrick A² being shown in Fig. 5.

The winding-drum B is mounted upon a main frame C and is normally loose—that is to say, it is loose when the driving power is disconnected from it, whereby the weight of a tool on the free end of the rope or cable portion which depends from an elevated pulley on the derrick will draw the rope or cable in a direction to cause the winding-drum to revolve and unwind and pay out the rope or cable, while, on the other hand, when driving power is applied to the drum the latter will be revolved in a direction to wind up the rope or cable, so as to raise the tool from the well. As a means for alternately applying and disconnecting the driving power to and from the drum the latter is provided with a spur-gear D, and a rotary power-driven shaft 1 is provided with a power-transmitting clutch device consisting of a pinion E, splined or keyed to slide longitudinally upon the shaft and having a hub portion 2, provided with a loose collar 3, which is link-connected with a shifting lever F. By adjusting this lever as in Fig. 2 the driving-pinion will be left free to turn and pay out the rope or cable, and by reversing the lever the pinion will be thrown in clutch with the relatively large spur-gear, whereby power from the continuously-running shaft will be imparted to the drum, which will thereupon be driven in a direction to wind up the rope or cable, and thereby raise the tool from the well.

The rotary power-driven counter-shaft 1 is arranged parallel with the axis of the winding-drum, and the latter has one of its journals or axle ends provided with the spur-gear D and also projected therefrom to afford a bearing for a loose collar 4, upon which the shifting lever F is pivoted. The spur-gear is also provided with a projecting hub portion 5, having a plane peripheral face and forming

a brake-wheel for a brake-band 6, which, as shown in Fig. 3, can be operated by a band-tightener G. The brake device thus arranged can be employed when the shifting driving-
5 pinion is thrown out of mesh with the relatively large spur-gear on the winding-drum, so as to regulate the speed of the descending tool, and when the pinion is thrown into mesh with the spur-gear the drum will operate to
10 wind up the rope or cable without sudden jerk and strain upon, and therefore without injury to, the rope or cable, it being observed that with long lengths of rope or cable the avoidance of sudden jerk and strain at the ini-
15 tial movement is a matter of considerable importance, particularly where there happens to be some slack in the rope or cable portion between the drum and the tool.

The counter-shaft 1 is operated from a ro-
20 tary power-driven shaft 7, having secured thereon a large friction-wheel 8, which engages a smaller friction-wheel 9, secured upon the counter-shaft 1, this arrangement being simple and compact and avoiding a multi-
25 plicity of toothed gear-wheels with their well-known objectionable features, such as expense in making and liability of breakage of teeth.

In order to alternately pull and slacken the rope or cable, so as to produce a jumping
30 motion on the part of the tool and to attain a relatively large extent of such jumping or re-
ciprocating movement, a vibratory beam H is pivotally supported at one end portion upon the main frame C and arranged to rise from
35 its pivotal support, as in Figs. 1 and 4. This vibratory beam is connected with the rope or cable in a way to exert a lateral pull upon the portion of the rope or cable between the winding-drum and the overhead pulley at top
40 of the derrick and in a direction away from the derrick when the beam swings in a direc-
tion away from the derrick and to slacken up on the rope or cable, so as to permit the tool to drop when the beam is swung toward the
45 derrick. The vibratory beam H is operated from the main driving-shaft 7 by means of an eccentric I, which is secured upon such shaft and arranged between the beam and a yoke-strap I', secured upon the latter. By
50 thus arranging the beam to extend upwardly from its pivotal or fulcral support it can be so nearly balanced as to permit the application of the actuating power relatively near its pivotally-supported lower end. With such
55 arrangement the beam forms a long lever with the power applied between its ends, so as to form a short arm, which is fulcrumed on the main frame at a point below the power, and a long arm, which extends upwardly from
60 the point at which the power is applied and which connects with the rope or cable, the stroke of the drilling-tool being proportional to the extent of swing on the part of the lever and the point of connection between the
65 lever and the rope or cable, which in both

Figs. 1 and 4 is at a point considerably higher than the point at which the power is applied to the lever.

In Figs. 1 and 5 the vibratory beam H is provided with an idler sheave or pulley K, supported upon the upper portion of its long arm, and the rope or cable from the winding-drum is carried therefrom to and about an idler sheave or pulley L on standard C' of the main frame C, thence to and about the pulley K on the vibratory beam or lever H, and thence up to an overhead pulley A', Fig. 5, at the top of the derrick A². By applying the operating power to this beam or lever at a point relatively near its lower pivotally-supported end and applying pulley K at a point relatively high up on the upwardly-extending long-arm portion of such beam or lever the arc which is traversed by the upper end of the beam or lever will be of much greater ex-
85 tent than the arc traversed by such beam or lever at the point where power is applied, and hence with a comparatively limited extent of throw on the point of an eccentric the pulley K will have a comparatively wide range of 90 bodily swing, which is particularly effective in spudding, where a considerable extent of rise and drop on the part of the spudding-tool is desirable. The arrangement of the beam or lever H relatively to the drum and 95 derrick also permits the action of the beam or lever to exert a comparatively large extent of pull on the rope or cable, it being obvious that when the beam is swung to the right or away from the derrick it will draw a portion 100 of the rope or cable downwardly and away from the top of the derrick and also draw a portion of the rope or cable in a direction laterally away from the derrick, whereby when the beam or lever is swung in a reverse direc-
105 tion it will slacken up on said two portions of the rope or cable and permit the tool to drop to an extent proportionally to the extent to which such rope or cable portions had been drawn away from the derrick by the beam or 110 lever.

In Fig. 4 the vibratory beam or lever H is connected with the rope or cable through the medium of a second vibratory beam or lever H', which is actuated from the vibratory beam 115 or lever H by a link or pitman connection M and a rope or cable N, attached at one end to the beam or lever H' and attached at its opposite end to a member 10, with which the rope or cable A has a shifting connection, the 120 member 10 being a guide device—such as a sheave or, as shown, a shoe adapted to embrace said rope or cable A. With this arrangement the vibratory beam or lever H' is pivotally supported at its lower end and ar-
125 ranged back of and in position generally corresponding with the vibratory beam or lever H, and in order to adjustably vary the stroke of the connection between the link or connect-
ing rod or pitman M and the vibratory beam 130

or lever H' can be adjustably shifted along the latter—as, for example, the link M can be attached to the beam or lever H' by a pivot 11, inserted through some one of a series of 5 holes 12 in such beam or lever—and in like manner a clevis 13, to which one end of the pull rope or cable N is secured, can be adjustably attached to the vibratory beam or lever H' by a pin or pivot 14 inserted through 10 some one of the said series of holes 12 in such beam or lever. By this arrangement the extent of vertical movement on the part of the tool can be considerably augmented, and by adjusting the connection between the link M and rear vibratory beam or lever H' the extent of such movement can be varied.

As the work progresses the rope or cable can be caused to pay out from the winding-drum by loosening the brake-band upon the 20 brake-wheel, so as to permit the winding-drum to run loose, and when desired the pinion E can be shifted into mesh with the spur-gear D for the purpose of causing the driving power to operate the winding-drum in a 25 direction to wind the rope or cable thereon, and thereby raise the tool from the well.

I have in following Claim 1 described an improvement common to both Figs. 1 and 4, a prominent feature of said Fig. 4 being 30 the rope or cable N, which may be termed a "jerk-line," arranged to exert lateral pull upon the main rope or cable A. Obviously this jerk-line could be attached to beam H and beam H' dispensed with, or beam H can 35 be dispensed with and an ordinary strap for eccentric I can be connected with the beam H', the jerk-line being attached to the latter.

What I claim as my invention is—

1. In a well-machine, a substantially up-

right vibratory beam pivotally supported at 40 its lower end; means for operating the beam consisting of an eccentric applied to it at a point whereby the length of beam portion above the eccentric is greater than the length of beam portion below such eccentric; a winding-drum arranged between the vibratory beam and the derrick; a rope or cable which is carried upwardly from the winding-drum to and over an overhead pulley at the upper portion of the derrick; and connection between 45 the upper portion of the vibratory beam and the portion of rope or cable between the winding-drum and the overhead pulley on the derrick, said connection being arranged to permit the swing of the vibratory beam in a 50 direction away from the derrick to exert a lateral pull upon said rope or cable portion at a point between the winding-drum and the overhead pulley on the derrick.

2. In a well-machine, a winding-drum; a 55 rope or cable passing from the winding-drum to an overhead pulley; a substantially upright vibratory beam provided with a sheave about which the portion of the rope or cable between the winding-drum and the overhead 60 pulley passes; and a device for vibrating the beam applied thereto at a point below the sheave thereon; the beam being pivotally supported below the device for causing it to vibrate, and being arranged to permit its sheave 65 to exert a lateral pull upon the rope or cable during the swing of such beam in one direction.
